UNITED STATES PATENT OFFICE

ROBERT Y. McCULLOUGH, OF SCHENECTADY, NEW YORK, ASSIGNOR TO GENERAL ELECTRIC COMPANY, A CORPORATION OF NEW YORK

CONTROL SYSTEM

Application filed January 22, 1929. Serial No. 334,314.

My invention relates to control systems and particularly to a system for automatically controlling the connections between a plurality of normally independently energized circuits and an auxiliary source of current therefor.

One object of my invention is to provide an arrangement for automatically connecting two normally independently energized circuits together when either of the circuits becomes deenergized while the other is energized, and for automatically connecting both of the circuits to an auxiliary source of current when both of the circuits are simultaneously deenergized.

Another object of my invention is to provide an arrangement whereby an overload on either of two circuits when they are connected together and to an auxiliary source effects the disconnection of the overloaded circuit from the auxiliary source and prevents the reconnection of the disconnected circuit thereto whereas an overload on either of the two circuits when they are connected together but are not connected to the auxiliary source merely effects the disconnection of said circuits from each other without preventing the automatic reconnection thereof to the auxiliary source.

My invention will be better understood from the following description when taken in connection with the accompanying drawing and its scope will be pointed out in the appended claims.

In the accompanying drawing, which diagrammatically shows an arrangement embodying my invention for controlling the connections between two normally disconnected circuits and an auxiliary source of current, 1 and 2 represent two electric circuits, which for example, may be separate sections of a railway signalling system. The circuits 1 and 2 are normally disconnected from each other and are normally energized, independently of each other, from the same or different source of current. As shown in the drawing, the circuit 1 is arranged to be connected to a suitable source of current 3 by means of an overload circuit breaker 4 and the circuit 2 is arranged to be connected to a suit-

able source of current 5 by means of an overload circuit breaker 6. The circuit breakers 4 and 6 may be of any suitable type examples of which are well known in the art.

The circuits 1 and 2 are arranged to be connected together by means of a connecting bus 7 which is arranged to be connected to the circuits 1 and 2 by means of suitable switches 8 and 9 respectively. 10 represents an auxiliary source of current which is arranged to be connected to the connecting bus 7 by means of a suitable switch 11 so that it supplies current to both of the circuits 1 and 2 when the switches 8, 9 and 11 are closed.

In certain systems of electric distribution such as railway signalling systems, it is very essential that the various sections of the system should be energized at all times. Therefore, it is necessary to provide an arrangement for reenergizing a deenergized section from some other source as soon as possible after the normal source supplying current thereto fails. In accordance with my invention I provide an arrangement whereby a predetermined decrease in the voltage across either the circuit 1 or 2 while the other is normally energized effects the closing of the switches 8 and 9 so that the circuits are connected together and the deenergized circuit is supplied from the normal circuit and whereby the auxiliary source 10 is connected to both of the circuits to supply current thereto when the voltages across both of the circuits 1 and 2 simultaneously remain below predetermined values for a predetermined time.

For accomplishing these results, I provide two time relays 14 and 15 which are respectively connected so that they are energized in response to the voltages across the circuits 1 and 2. The relay 14 is arranged to effect the energization of a control relay 16 when the voltage across the circuit 1 remains above a predetermined value for a predetermined time and to effect the deenergization of the control relay 16 when the voltage across the circuit 1 remains below a predetermined value for a predetermined time. When the control relay 16 is energized and the auxiliary

source 10 is disconnected from the bus 7, the control relay 16 is arranged to complete an energizing circuit for a control relay 17.

The time relay 15 is connected so that it is energized in accordance with the voltage 5 across the circuit 2 and is arranged to effect the energization of the control relay 18 when the voltage across the circuit 2 remains above a predetermined value for a predetermined time and to effect the deenergization of the 10 control relay 18 when the voltage across the circuit 2 remains below a predetermined value for a predetermined time. When the control relay 18 is energized and the auxiliary source 10 is disconnected from the bus 7 the 15 control relay 18 is arranged to complete an energizing circuit for a control relay 19.

When the voltage across the circuit 1 is normal so that control relay 17 is energized 20 and the voltage across the other circuit 2 is below a predetermined value so that the contacts 20 of the time relay 15 are closed, an energizing circuit is completed for a control relay 22 which when energized completes an 25 energizing circuit for the closing coil 23 of the switch 8. The switch 8 when closed connects the circuit 1 to the connecting bus 7 and also completes an energizing circuit for the control relay 24 which, in turn, completes an 30 energizing circuit for the closing coil 25 of the switch 9 so that circuit 2 is also connected to the bus 7.

When the voltage across the circuit 2 is normal so that control relay 19 is energized 35 and the voltage across the circuit 1 is below a predetermined value so that the contacts 28 of the time relay 14 are closed, an energizing circuit is completed for the control relay 24 which, in turn, completes an energizing circuit for the closing coil 25 of the switch 9 to 40 connect the circuit 2 to the connecting bus 7. The closing of the switch 9 also completes an energizing circuit for the control relay 22 which, in turn, completes an energizing circuit for the closing coil 23 of the switch 8 so 45 that the circuit 1 is also connected to the connecting bus 7.

In order to effect the connection of the auxiliary source 10 to the bus 7 and to both of 50 the circuits 1 and 2 when they are simultaneously deenergized, I provide a voltage relay 30 which is connected so as to be responsive to the voltage of the auxiliary source 10. When the auxiliary source voltage is above a predetermined value, the voltage relay 30 maintains its contacts 31 closed and when the auxiliary source voltage is below a predetermined value the relay 30 maintains its contact 31 opened. I also provide a control 55 relay 32 which is controlled by the relays 16 and 18 so that it is energized when the voltage of both of the circuits 1 and 2 are below predetermined values. When the relays 30 and 32 are simultaneously energized, a circuit 60 is completed for a control relay 33 which

when energized completes an energizing circuit for the closing coil 23 of the switch 8 the closing coil 25 of the switch 9 and the closing coil 34 of the switch 11 so that the auxiliary source 10 is connected to the bus 7 and the circuits 1 and 2.

In order to effect the opening of the switch 8 when a fault occurs on the circuit 1, while the switch is closed I provide a lockout relay 40 which is connected in any suitable manner so that it is energized in accordance with the current through the switch 8. As shown in the drawing, the lockout relay 40 is connected to the secondary of a current transformer 41, the primary of which is connected in series with the circuit 1 when the switch 8 is closed. The lockout relay 40 is arranged to open contacts in the circuit of the control relay 22 and thereby effect the opening of switch 8 when the current through the switch 8 exceeds a predetermined value.

The opening of the switch 9 is effected in a similar manner by means of a lockout relay 42 which is connected to the secondary of a current transformer 43, the primary of which is connected in series with the circuit 2 when the switch 9 is closed. The lockout relay 42 is arranged to open contacts in the circuit of the control relay 24 when the current through the switch 9 exceeds a predetermined value.

The lockout relays 40 and 42 are preferably arranged in any suitable manner, examples of which are well known in the art, so that the resetting of their respective contacts is manually controlled so that a subsequent automatic reclosing of the associated switch cannot be effected until an operator has had an opportunity to investigate and determine whether or not the conditions warrant the reclosing of the locked out switch.

In accordance with my invention, I provide an arrangement whereby the lockout relays 40 and 42 operate to effect the locking out of their associated switches only when the auxiliary source 10 is supplying current to the connecting bus 7. This result is accomplished in the particular arrangement shown in the drawing by providing the switch 11 with auxiliary contacts which shunt the operating coils of the lockout relays 40 and 42 when the switch 11 is open. Such an arrangement is desirable in order to prevent both of the switches 8 and 9 from being locked out when a fault occurs on one of the circuits when it is being supplied with current from the other circuit. When a fault occurs under such conditions it is desirable to have the normal circuit disconnected from its source of current by means of its associated overload circuit breaker so that both of the circuits 1 and 2 become simultaneously deenergized and effect the connection of the auxiliary source 10 thereto. If the fault is still connected to one of the circuits when

the auxiliary source is connected to both of the circuits it is then desirable to have the lockout relay associated with the switch in the faulty circuit operate to effect the locking out of the switch in the faulty circuit without effecting the opening of the switch between the auxiliary source and the normal circuit.

In order to supply current from the circuits 1 and 2 and the auxiliary source 10 to operate the various control devices. I provide the potential transformers 44, 45 and 46 the primary windings of which are respectively connected across the circuits 1 and 2 and the source 10 and the secondary windings of which are respectively connected by control switches 47, 48 and 49 to the control devices which are arranged to be energized therefrom.

The operation of the arrangement shown in the drawing is as follows. Under normal conditions the circuit breakers 4 and 6 are closed and the switches 8, 9 and 11 are open so that the circuits 1 and 2 are disconnected from each other and are respectively energized by the sources 3 and 5. Also the control switches 47, 48 and 49 are normally closed.

After the control switch 47 is closed and the voltage across the load circuit 1 has remained above a predetermined value for a predetermined time the contacts 50 of the relay 14, which is connected across the secondary of the transformer 44, are closed so that the control relay 16 is also connected across the secondary of the transformer 44. When the relay 16 is energized and the switch 11 is open an energizing circuit is completed for the control relay 17 from one secondary terminal of the transformer 44 through switch 47, contacts 51 of the relay 16, conductor 52, auxiliary contacts 53 on the switch 11, conductor 54, coil of relay 17, conductor 55, control switch 47 to the other secondary terminal of the transformer 44. Therefore, under normal operating conditions the relays 14, 16 and 17 are energized.

After the control switch 48 is closed and the voltage across the circuit 2 has remained above a predetermined value for a predetermined time, the relay 15 which is connected directly across the secondary winding of the transformer 45 by the control switch 48, closes its contacts 56 and connects the winding of the control relay 18 across the secondary winding of the transformer 45. When the control relay 18 is energized and the switch 11 is open, an energizing circuit is completed for the control relay 19 from one secondary terminal of the transformer 45 through control switch 48, conductor 58, contacts 59 of relay 18, conductor 60, auxiliary contacts 61 on switch 11, conductor 62, coil of relay 19, conductor 55, control switch 48 to the other secondary terminal of the

transformer 45. Therefore, under normal operating conditions the control relays 15, 18 and 19 are also energized.

If the auxiliary source 10 is also energized, the control relay 30 which is connected across the secondary winding of the transformer 46 by the control switch 49 is also energized so that its contacts 31 are closed.

It will now be assumed that a fault occurs on the circuit 1 which causes the overload circuit breaker 4 to open and disconnect the circuit 1 from the source 3. After a predetermined time the voltage relay 14 opens its contacts 50 and closes its contacts 28. The opening of the contacts 50 effects the deenergization of the control relay 16 which, in turn, opens at its contacts 51 the above-traced circuit for the control relay 17. The closing of the contacts 28 of the relay 14 completes an energizing circuit for the control relay 24. This circuit is from one secondary terminal of the transformer 45 through the switch 48, conductor 58, contacts 59 of relay 18, conductor 60, auxiliary contact 61 on switch 11, conductor 62, contacts 64 of relay 19, conductor 65, contacts 28 of relay 14, conductor 66, coil of relay 24, conductor 67, contact 68 of lockout relay 42, conductor 55, control switch 48 to the other secondary terminal of the transformer 45. Control relay 24 by closing its contacts 69 connects conductor 62 to conductor 66 and thereby completes a locking circuit for itself which is independent of the contacts 28 of the voltage relay 14 so that the control relay 24 is not deenergized by the subsequent energization of the circuit 1. Relay 24 by closing its contacts 70 completes an energizing circuit for the closing coil 25 of the switch 9 so as to effect the connection of the circuit 2 to the connecting bus 7. This energizing circuit of the closing coil 25 is from one secondary terminal of the transformer 45 through the switch 48, conductor 58, contacts 59 of the relay 18, conductor 60, auxiliary contacts 61 on switch 11, conductor 62, contacts 70 of relay 24, conductor 71, closing coil 25 of switch 9, conductor 55, control switch 48 to the other secondary terminal of the transformer 45. The switch 9 by closing its auxiliary contacts 72 completes an energizing circuit for the control relay 22. This energizing circuit is from one secondary terminal of the transformer 45 through the control switch 48, conductor 58, contacts 59 of relay 18, conductor 60, auxiliary contacts 61 on switch 11, conductor 62, auxiliary contact 72 on switch 9, conductor 73, contacts 74 of relay 33, conductor 75, coil of relay 22, conductor 76, contact 77 of lockout relay 40, conductor 55, control switch 48 to the other secondary terminal of the transformer 45.

Relay 22 by closing its contacts 78 and 79 completes an energizing circuit for the closing coil 23 of the switch 8 so as to connect the circuit 1 to the connecting bus 7 which is al-

ready connected to the energized circuit 2 by means of the switch 9. This energizing circuit for the closing coil 23 is from one secondary terminal of the transformer 46 through the control switch 48, conductor 58, contacts 59 of relay 18, conductor 60, auxiliary contacts 61 on switch 11, conductor 62, auxiliary contacts on switch 9, conductor 73, contact 74 of relay 33, conductor 75, contact 78 of relay 22, conductor 54, contact 79 of relay 22, conductor 81, closing coil 23 of switch 8, conductor 55, control switch 48 to the other secondary terminal of the transformer 45.

As soon as the switch 8 closes and normal voltage is restored across the circuit 1 the voltage relay 14 is energized. If the fault has cleared, the voltage relay 14, after a predetermined time, effects the energization of the control relays 16 and 17 in the manner heretofore described. The energization of these control relays, however, does not effect the deenergization of the control relays 22 and 24 and the opening of the switches 8 and 9 because of the locking circuit which the relay 22 completed through its contacts 69.

Therefore, it will be observed that when the voltage across the circuit 1 fails while the circuit 2 is energized the switches 8 and 9 are closed to connect the deenergized circuit 1 to the energized circuit 2.

If the fault is still connected to the circuit 1 when the switch 8 is closed, the fault causes the overload circuit breaker 6 to disconnect the source 5 from the circuit 2 so that both of the circuits 1 and 2 are deenergized. Consequently, all of the control devices except the relay 30 which is connected across the secondary winding of the transformer 46, are also deenergized.

Since the switch 11 is open, the fault on the circuit 1 does not effect the operation of the lockout relays 40 and 42 at this time because the operating coil of the lockout relay 40 is short-circuited by the contacts 94 of the relay 22 and the auxiliary contacts 95 on switch 11 and the operating coil of the lockout relay 42 is short-circuited by the contacts 96 of relay 24 and auxiliary contacts 97 on the switch 11.

When both of the control relays 16 and 18 are deenergized and the relay 30 is energized, an energizing circuit is completed for the control relay 32. This energizing circuit is from one secondary terminal of the transformer 46 through the control switch 49, conductor 82, coil of relay 32, resistor 83, conductor 55, control switch 49 to the other secondary terminal of the transformer 46. It will be observed that under normal conditions the coil of the relay 32 is shunted by the contacts 84 of the control relay 16 if the voltage of the circuit 1 is above a predetermined value and by the contacts 85 of the control relay 18 if the voltage of the circuit

2 is above a predetermined value. Therefore, it is necessary for the voltages of both of these circuits to be below predetermined values in order for the relay 32 to be energized. When the relay 32 is energized, it completes an energizing circuit for the control relay 33 from one secondary terminal of the transformer 46 through the control switch 49, conductor 82, contacts 31 of relay 30, conductor 87, coil of relay 33, conductor 88, contacts 89 of relay 32, conductor 55, control switch 49 to the other secondary terminal of the transformer 46. Relay 33 by closing its contacts 90 completes an energizing circuit for the closing coil 34 of the switch 11 and by closing its contacts 91 and 92, complete respectively energizing circuits for the control relays 22 and 24. The energizing circuit for the closing coil 34 of the switch 11 is from one secondary terminal of the transformer 46 through control switch 49, conductor 82, contacts 90 of relay 33, conductor 93, closing coil 34 of switch 11, conductor 55, control switch 49 to the other secondary terminal of the transformer 46. The closing coil 34, when energized, closes the switch 11 so that the auxiliary source 10 is connected to the connecting bus 7.

The energizing circuit for the control relay 22 is from one secondary terminal of the transformer 46 through the control switch 49, conductor 82, contacts 91 of the relay 33, conductor 75, coil of relay 22, conductor 76, contacts 77 of lockout relay 40, conductor 55, control switch 49 to the other secondary terminal of the transformer 46. Control relay 22 by closing its contacts 78 completes an energizing circuit for the closing coil 23 of the switch 8 so that the circuit 1 is connected to the connecting bus 7. This energizing circuit is from one secondary terminal of the transformer 46 through the control switch 49, conductor 82, contacts 91 of relay 33, conductor 75, contacts 78 of relay 22, conductor 54, contacts 79 of relay 22, conductor 81, closing coil 23 of switch 8, conductor 55, control switch 49 to the other secondary terminal of the transformer 46.

The energizing circuit for the control relay 24 is from one secondary terminal of the transformer 46 through control switch 49, conductor 82, contacts 92 of relay 33, conductor 66, coil of relay 24, conductor 67, contacts 68 of lockout relay 42, conductor 55, control switch 49 to the other secondary terminal of the transformer 46. Relay 24, by closing its contacts 69 and 70, completes an energizing circuit for the closing coil 25 of the switch 9 so that the circuit 2 is connected to the connecting bus 7. This energizing circuit is from one secondary terminal of the transformer 46 through control switch 49, conductor 82, contacts 92 of relay 33, conductor 66, contacts 69 of relay 24, conductor 62, contacts 70 of relay 24, conductor 71, closing coil 25 of the

switch 9, conductor 55, control switch 49 to the other secondary terminal of transformer 46.

Therefore, it will be observed that when the voltages of both of the circuits 1 and 2 are below predetermined values, the switches 8, 9 and 11 are closed to connect the auxiliary switch 10 to the circuits 1 and 2.

When the switch 11 closes its auxiliary contacts 98, it completes a circuit around the contacts 89 of relay 32 in the circuit of the control relay 33 so that the control relay 33 is not deenergized when the control relay 32 is deenergized in response to the energization of either the relay 16 or the relay 18 when the circuits 1 and 2 are reenergized. The switch 11 by opening its auxiliary contacts 53 and 61 prevents the control relays 17 and 19 from being energized in response to the energization of the circuits 1 and 2 when the switches 8 and 9 are closed.

If the fault on the circuit 1 has cleared prior to the closing of the switches 8 and 11, the switches 8, 9 and 11 remain closed and the auxiliary source 10 continues to supply current to both of the circuits 1 and 2. If, however, the fault is still connected to the circuit 1 when the switches 8 and 11 are closed the overcurrent through the switch 8 causes the lockout relay 40 to open its contacts 77 in the heretofore traced circuit of the closing coil of the relay 22. The relay 22 by opening its contacts 78 and 79 opens the heretofore traced circuit for the closing coil 23 of the switch 8 to disconnect the faulty circuit 1 from the auxiliary source 10. Since the over-current which the auxiliary source 10 supplies to the fault circuit 1 does not flow through the primary winding of the transformer 43 the lockout relay 42 is not operated at this time to effect the deenergization of the control relay 24 and the opening of the switch 9. Therefore, the auxiliary source 10 continues to supply current to the normal circuit 2.

When both of the circuits 1 and 2 are independently energized and a fault occurs on the circuit 2 so that the source 5 is disconnected from the circuit 2 by the opening of the overload circuit breaker 6, the voltage relay 15 by closing its contacts 20 completes an energizing circuit for the control relay 22. This energizing circuit is from one secondary terminal of the transformer 44 through the control switch 47, contacts 51 of relay 16, conductor 52, auxiliary contacts 53 on switch 11, conductor 54, contacts 99 of relay 17, conductor 100, contacts 20 of relay 15, conductor 75, coil of relay 22, conductor 76, contacts 77 of lockout relay 40, conductor 55, control switch 47 to the other secondary terminal of the transformer 44. Control relay 22 by closing its contacts 79 completes an energizing circuit for the closing coil 23 of the switch 8 so that the circuit 1 is connected

to the connecting bus 7. This energizing circuit for the closing coil 23 is from one secondary terminal of the transformer 44 through the control switch 47, contacts 51 of relay 16, conductor 52, auxiliary contacts 53 on switch 11, conductor 54, contacts 79 of relay 22, conductor 81, closing coil 23 of switch 8, conductor 55, control switch 47 to the other secondary terminal of the transformer 44.

When the switch 8 closes, its auxiliary contacts 101 complete an energizing circuit for the control relay 24. This energizing circuit is from one secondary terminal of the transformer 44 through the control switch 47, contacts 51 of relay 16, conductor 52, auxiliary contacts 53 of switch 11, conductor 54, auxiliary contacts 101 on switch 8, conductor 102, contacts 103 of relay 33, conductor 66, coil of relay 24, conductor 67, contacts 68 of lockout relay 42, conductor 55, control switch 47 to the other secondary terminal of the transformer 44. Control relay 24 by closing its contacts 69 and 70 completes an energizing circuit for the closing coil 25 of the switch 9 so as to connect the circuit 2 to the connecting bus 7. This energizing circuit for the closing coil 25 is from one secondary terminal of the transformer 42 through the control switch 47, contacts 51 of relay 16, conductor 52, auxiliary contacts 53 on switch 11, conductor 54, auxiliary contacts 101 on switch 8, conductor 102, contacts 103 of relay 33, conductor 66, contacts 69 of relay 24, conductor 62, contacts 70 of relay 24, conductor 71, closing coil 25 of the switch 9, conductor 55, control switch 47 to the other secondary terminal of the transformer 44.

If the fault on the circuit 2 is cleared prior to the closing of the switches 8 and 9 these switches remain closed and the circuit 2 is supplied with current from the circuit 1. If, however, the fault is still connected across the circuit 2, the overload circuit breaker 4 is opened as soon as the switches 8 and 9 are closed so as to disconnect the source 3 from the circuit 1. Both of the circuits 1 and 2 are then deenergized and the auxiliary source 10 is connected to both of the sources in the manner above described. If the fault is still connected across the circuit 2 when the switches 9 and 10 are closed, the lockout relay 42 operates to open its contacts 68 and effect the deenergization of the control relay 24 and the closing coil 25 of the switch 9 so that the circuit 2 is disconnected from the auxiliary source 10.

While I have, in accordance with the patent statutes, shown and described my invention as applied to a particular system and as embodying various devices diagrammatically indicated, changes and modifications will be obvious to those skilled in the art and I, therefore, aim in the appended claims to cover all such changes and modifications

as fall within the true spirit and scope of my invention.

What I claim as new and desire to secure by Letters Patent of the United States, is:

- 5 1. In combination, two normally disconnected independently energized circuits, a source of current normally disconnected therefrom, and means responsive to the voltages of said circuits for effecting the connection of said circuits together when the voltage of one of said circuits decreases below a predetermined value while the voltage of the other circuit is above a predetermined value and for effecting the connection of both of said circuits to said source when the voltages of both of said circuits are simultaneously below predetermined values.
- 10 2. In combination, two normally disconnected circuits, a connecting bus, a circuit breaker between said bus and each circuit, means responsive to the voltages of said circuits for effecting the closing of said circuit breakers when the voltage of either of said circuits decreases below a predetermined value while the voltage of the other circuit is above a predetermined value, a source of current, and means responsive to the voltages of said circuits for effecting the connection of said source to said bus and the closing of both of said circuit breakers when the voltages of both of said circuits are simultaneously below predetermined values.
- 15 3. In combination, two normally disconnected circuits, a connecting bus, a circuit breaker between said bus and each circuit, means responsive to the voltages of said circuits for effecting the closing of each circuit breaker when the associated circuit voltage is above a predetermined value and the other circuit voltage is below a predetermined value, means controlled by said circuit breakers for effecting the closing of the other circuit breaker when one is closed, a source of current, a third circuit breaker for connecting said source to said bus, means responsive to the voltages of said circuits for effecting the closing of said third circuit breaker when the voltages of both of said circuits are simultaneously below predetermined values, and means controlled by said third circuit breaker for closing both of said other circuit breakers when said third circuit breaker is closed.
- 20 4. In combination, two normally disconnected circuits, a connecting bus, a circuit breaker between said bus and each circuit, means responsive to the voltages of said circuits for effecting the closing of each circuit breaker when the associated circuit voltage is above a predetermined value and the other circuit voltage has remained below a predetermined value for a predetermined time, a source of current, a third circuit breaker for connecting said source to said bus, means responsive to the voltages of said circuits for

effecting the closing of said third circuit breaker when the voltages of both of said circuits remain below predetermined values for a predetermined time and means controlled by said third circuit breaker for closing both of said other circuit breakers in response to the closing of said third circuit breaker and for closing the other of said first mentioned circuit breakers when one of said first mentioned circuit breakers is closed by said first mentioned voltage responsive means while said third circuit breaker is open.

5 5. In combination, two normally disconnected circuits, a source of current normally disconnected from said circuits, means including a circuit breaker for connecting said circuits together, means including said circuit breaker for connecting one of said circuits to said source, and overload responsive means associated with said circuit breaker for effecting the opening thereof in response to the current therethrough only when said circuit breaker connects said source to said one of said circuits.

6. In combination, two normally disconnected circuits, a source of current normally disconnected from said circuits, an interconnecting bus, a circuit breaker between each circuit and said bus, current responsive means associated with each circuit breaker for effecting the opening thereof, means for connecting said source to said bus, and means for preventing each overcurrent responsive means from effecting the opening of its associated circuit breaker in response to an overcurrent therethrough when said source is disconnected from said bus.

7. In combination, two normally disconnected circuits, a source of current normally disconnected from said circuits, an interconnecting bus, a circuit breaker between each circuit and said bus, overcurrent responsive means associated with each circuit breaker for effecting the opening thereof, a circuit breaker between said source and bus, and means controlled by said last mentioned circuit breaker for short-circuiting said overcurrent responsive means when said last mentioned circuit breaker is open.

8. In combination, two normally disconnected circuits, a source of current, a plurality of switches controlled by the voltages of said circuits for connecting said circuits together when the voltage of one of said circuits is below a predetermined value while the voltage of the other circuit is above a predetermined value and for connecting said source to both of said circuits when the voltages of both of said circuits are simultaneously below predetermined values, overcurrent responsive means associated with each of the switches which connects said circuits together for effecting the opening thereof in response to the current therethrough, and means for controlling the op-

eration of said overcurrent responsive means so that they effect the opening of the associated switches only when said source is connected to one of said circuits.

5 9. In combination, two normally disconnected circuits, a connecting bus, a switch between each circuit and said bus, means responsive to the voltages of said circuits for effecting the closing of said switches when 10 the voltage of one of said circuits is below a predetermined value while the voltage of the other circuit is above a predetermined value, a source of current, a circuit breaker for connecting said source to said bus, means 15 responsive to the voltages of said circuits for effecting the closing of said circuit breaker and of said switches when the voltages of both of said circuits are simultaneously below predetermined values, means associated with 20 each of said switches for effecting the opening thereof in response to the current therethrough and for preventing the automatic reclosing thereof in response to the operation of said voltage responsive means, and means 25 for controlling said opening means so that each effects the opening of its associated switch only when said source is supplying current to said bus.

10. In combination, two normally disconnected circuits, a connecting bus, a switch between each circuit and said bus, means responsive to the voltages of said circuits for effecting the closing of said switches when 30 the voltage of one of said circuits is below a predetermined value while the voltage of the other circuit is above a predetermined value, a source of current, a circuit breaker for connecting said source to said bus, means responsive to the voltages of said circuits 35 for effecting the closing of said circuit breaker and of said switches when the voltages of both of said circuits are simultaneously below predetermined values, means associated with each of said switches for effecting the opening 40 thereof in response to the current therethrough and for preventing the automatic reclosing thereof in response to the operation of said voltage responsive means, and means 45 controlled by said circuit breaker for controlling said opening means so that each effects the opening of its associated switch only when said circuit breaker is closed.

In witness whereof, I have hereunto set my hand this 21st day of January, 1929.

55 ROBERT Y. McCULLOUGH.
